UNITED STATES PATENT OFFICE.

ALBERT CEDERLUND AND RICHARD GREENLEAF TURNER, OF WORCESTER, MASSACHUSETTS, ASSIGNEES TO CROMPTON & KNOWLES LOOM WORKS, OF WORCESTER, MASSACHUSETTS, A CORPORATION OF MASSACHUSETTS.

WEFT DETECTOR IN LOOM TRANSFERRER.

Application filed November 15, 1926. Serial No. 148,396.

This invention relates to improvements in weft detectors for weft replenishing looms more particularly of the type wherein the transerrer arm receives a regular downward movement toward the active shuttle on every alternate beat of the loom, and it is the principal object of the invention to provide a side slipping feeler for the transerrer arm so arranged as to be moved toward the surface to be detected by energy transmitted to it through a resilient or cushioning device.

In Patent No. 1,372,316 to Ryon there is shown a loom having a transerrer arm movable downwardly on alternate beats of the loom to present a detector to the weft in the shuttle when the lay is in its extreme forward position. In co-pending patent application Ser. No. 120,491 filed by Turner there is shown a yieldable lever held in raised position relatively to the transerrer arm and tending by reason of the energy stored therein to move downwardly toward the weft after the transerrer arm has been brought to rest. The detector in that instance is pivoted to the lever and the whole energy stored in the lever is transferred directly to the detector by a positive connection. This construction has been found, in certain instances, to result in undesirable pressure of the detector against the yarn, and it is an important object of our present invention to mount the detector for relative sliding movement on the lever which is pivoted to the transerrer arm and to impart the energy from the lever to the detector through a spring which as shown herein is of the compression type.

It is a still further object of our invention to provide a weft detector of the type specified wherein a single spring associated with the detector will operate to restore the same to normal position with respect to the supporting lever after an angular movement at the time of indication of weft exhaustion.

With these and other objects in view which will appear as the description proceeds, our invention resides in the combination and arrangement of parts hereinafter described and set forth in the claims.

In the accompanying drawings wherein we have shown a convenient embodiment of our invention,

Fig. 1 is a vertical section through that

part of a transerrer which extends parallel to and above the bobbin when the latter is in detecting position and showing the parts in the position they assume when a sufficient supply of weft is present.

Fig. 2 is a view similar to Fig. 1 but showing the parts moved to indicating position.

Fig. 3 is a vertical section on line 3—3 of Fig. 1.

Fig. 4 is a horizontal section on line 4—4 of Fig. 3, and

Fig. 5 is a detail end elevation of a portion of the supporting lever and detector taken in the direction of arrow 5, Fig. 1.

Referring to the drawings it will be seen that we have provided a transerrer arm 10 having an extension 11 which normally lies above the bobbin B when the latter is in detecting position on that side of the loom where the replenishing mechanism is located. Said extension has a heel 12 to engage the rings of the butt 13 of the bobbin and may have a web 14 to prevent upward movement of the central portion of the bobbin during transfer. Said extension 11 is provided with a slot 15 defined by parallel vertical walls 16 between which extends a supporting stud 17 on which is mounted for limited angular movement a detector supporting lever 18. Said lever 18 has a finger 19 which is normally held against a portion of the transerrer arm by a tension spring 20 connected to a lug 21 of the lever 18 and a screw 22 threaded into the transerrer arm.

A plunger 23 is movable in a cylindrical bore 24 extending longitudinally of the extension 11 and substantially parallel to the bobbin B. A compression spring 25 surrounds a portion of the plunger and lies between a web 26 rigid with the transerrer arm and the head 27 of the plunger and tends normally to move the latter to the right as shown in Fig. 1.

In order to control movement of the plunger 23 there may be provided a latch 28 pivoted at 29 to a fixed part of the transerrer arm and having a hooked end 30 to receive a notch 31 formed in the left hand end of the plunger 23. A depending tail 32 of the latch 28 is the means by which the latter may be moved in a counterclockwise direction around stud 29 at the time of indication of weft exhaustion to release the plunger 23, this movement of the latch be-

ing resisted by a small torsion spring 33 coiled around a part of stud 29 and having one end in engagement with the latch and the other end in engagement with the trans-
 5 ferrer arm so as to restore the latch 28 to its normal position after being swung in a left hand direction. The motion of the plunger 23 to the right under influence of spring 25 is limited by pin 34 which may
 10 engage the web 26 as shown in Fig. 2. The matter thus far described is the usual construction, downward movement of the trans-
 15 ferrer arm storing in the lever 18 energy which tends to keep the latter moving down-
 20 wardly after the transferrer arm reaches its lowest position and the head 27 of the plunger 23, when moved to the right as shown in Fig. 2, co-acting with an indicating lever not shown herein but fully set forth
 25 in the aforesaid patent and application, and our invention does not relate to the matter thus far described.

Our present improvements include means for transmitting the energy stored in lever
 25 18 to the weft detector and to means for re-
 20 storing the latter and holding the same in normal position. In carrying out our in-
 25 vention we provide the lever 18 with a coni-
 30 cal downwardly flaring tapered opening 40,
 35 and we further provide the lever 18 with a downwardly extending arm 41 to which is secured in any approved manner a small plate 42 having a slot 43 therein as shown more particularly in Figs. 1 and 4. The de-
 40 tector comprises a rod 44 movable through the tapered hole 40 and having secured to the lower end thereof a head 45 of non-circular cross-section substantially the same width as slot 43 but of less length, so that said head
 45 is free to move in the slot to the right from the position shown in Fig. 1. A compres-
 50 sion spring 46 surrounding the rod 44 lies be-
 55 tween the opening 40 and the head 45 and tends normally to push the detector down, such movement being limited by a finger 47 secured to the rod 44 and extending laterally from said rod in a direction opposite to the direction in which the detector swings at the time of indication. Said finger works in an
 60 upwardly flaring opening 48 defined by a pair of lugs 49 extending upwardly from the lever 18.

The yarn engaging portion of the detector may be made of a strip of sheet metal 50 having one end thereof secured to the head 45 and having the other end extending upwardly as at 51 in position to engage the depending tail 32. The under side of the detector 50 is provided with teeth 52 which are intended to be embedded in the yarn of the bobbin and are also located to one side of the axis of the rod 44. The detector is rounded as at 53 and a guard 54 prevents the tail 32 from being caught on the left hand side of
 65 upwardly extending end 51 of the detector.

When the transferrer is in its uppermost position the spring 46 will move the finger 47 to the bottom of the upwardly flaring opening 48 to the position shown in Fig. 2, and said spring will also tend to hold the rod 44 vertical because of the contact between the finger 47 and the lever 18 which is located to one side of the axis of rod 44. As the trans-
 70 ferrer arm reaches its lowermost position it will be brought to rest very quickly and the lever 18 will continue downwardly to press on the upper end of spring 46. The energy of the lever is communicated to the detector through the spring 46 to cause the detector to move downwardly into engagement with the yarn of the bobbin. The teeth 52 there-
 75 fore engage the surface to be detected under the pressure of such force as is transmitted through the spring 46.

If sufficient yarn for continued weaving is present the teeth 52 will be restrained against lateral movement and the end 51 of the detector will be held away from the tail 32. When insufficient weft for continued weaving is present the teeth 52 will slide along the wood of the bobbin to the position shown in Fig. 2, the end 51 engaging the tail 32 to rock the latch 28 in a counterclockwise direction to the position shown in Fig. 2, thus releasing the plunger 23 so that the same
 80 will be moved to the right to indicating position under action of spring 25. As soon as lever 18 has come to rest relatively to the transferrer arm spring 20 will contract to lift said lever and as the latter moves up-
 85 wardly the spring 46 acting through the head 45 and finger 47 will restore the detector to the normal position shown in Fig. 1.

From the foregoing it will be seen that we have provided a weft detector moved toward the surface to be detected by such energy de-
 90 rived from the carrying lever as can be transmitted through the spring 46 and that the detector is movable angularly with respect to its carrier lever as well as being slid-
 95 ably mounted thereon. It will further be seen that the pin 47 cooperates with the spring 46 to return the lever to normal position after each indicating movement.

Having thus described our invention, it will be apparent that changes and modifications may be made therein by those skilled in the art without departing from the spirit and scope of the invention, and we do not wish to be limited to the details herein disclosed but what we claim is:

1. In a weft detector for a weft replenishing loom having a transferrer arm receiving a movement toward the surface to be detected on each detecting beat of the loom, a weft detector carrier movably mounted on the trans-
 115 ferrer arm, a weft detecting element mounted on the carrier to move slidably with respect thereto on non-indicating detecting picks of the loom and angularly with respect
 120 to the carrier lever.

thereto on indicating picks, and yielding means interposed between the carrier and the element to transmit energy derived from the carrier to the element tending to move said 5 detecting element along the surface to be detected at substantial exhaustion of weft.

2. In a weft detector for a weft replenishing loom having a transferrer arm receiving a movement toward the surface to be detected on each detecting beat of the loom, a lever pivoted to the transferrer arm and normally held yieldingly in raised position, a detecting element movable on the lever to slide relatively thereto on non-indicating detecting beats of the loom and to move angularly relatively to the lever on indicating beats of the loom, and having a detecting surface out of vertical alignment with the point about which the detector moves angularly relative- 10 ly to the lever to engage the surface to be detected, and a yielding device interposed between the supporting lever and the detector, said yielding device transmitting energy from the lever to the detector, said detector 15 sliding along the surface to be detected at substantial exhaustion of weft.

3. In a weft detector for a weft replenishing loom having a transferrer arm receiving a movement toward the surface to be detected on each detecting beat of the loom, a carrying lever pivotally mounted on the transferrer arm and normally held yieldingly in raised position, a detector element mounted to slide on the lever on non-indicating detecting picks of the loom and also angularly movable with respect to the lever on indicating picks of the loom, a compression spring interposed between the lever and the detecting element and tending to hold the latter in lowered position, said detecting element having a detecting surface located to one side of the line of action of the spring, and means carried by the detecting element and projecting laterally therefrom to lie on 20 the opposite side of the spring, said spring and means holding said detecting element in normal position and tending to return the same to normal position after an indicating movement of the detecting element.

4. In a weft detector for a weft replenishing loom having a transferrer arm receiving a movement toward the surface to be detect-

ed on each detecting beat of the loom, a supporting member movably mounted with respect to the transferrer arm and normally held yieldingly in raised position, a detecting element mounted on the member for sliding an angular movement with respect thereto, resilient means interposed between the supporting member and the detector tending to hold the latter in lowered position, said detector having a detecting surface to engage the surface to be detected lying on one side of the line of action of the resilient means and said detector having a device on the other side of the line of action of the resilient means to engage the member, said resilient means cooperating with said device to hold the detector in normal position and to restore the same to normal position after an indicating movement thereof.

5. In a weft detector for a weft replenishing loom having a transferrer arm receiving a movement toward the surface to be detected on each detecting beat of the loom, a supporting member movably mounted on the transferrer arm and normally held yieldingly in raised position, a detecting element mounted on the supporting member for sliding and angular movement relatively thereto, resilient means for the central portion of the detecting element interposed between said detecting element and the supporting member, a detecting surface for the detector located below the resilient device and to one side of the line of action thereof, and a device above the resilient means and located on the other side thereof to engage the supporting member, said device and resilient means tending to hold the detector in normal position and to restore the same to normal position after an indicating movement thereof, said supporting member and the parts carried thereby moving toward the surface to be detected after the transferrer arm has been brought to rest, due to the energy stored in the supporting member, said resilient means transmitting energy from the supporting member to the detector.

In testimony whereof we have hereunto affixed our signatures.

ALBERT CEDERLUND.
RICHARD GREENLEAF TURNER.
